UNITED STATES PATENT OFFICE.

ZALMON G. SHOLES, OF WILMINGTON, DELAWARE, ASSIGNOR TO SHOLES STANDARD TYPEWRITER COMPANY, OF WILMINGTON, DELAWARE, A CORPORATION OF DELAWARE.

REMOVABLE MOUNTING FOR TYPE-WRITER CARRIAGES.

1,179,463.

Specification of Letters Patent. Patented Apr. 18, 1916.

Application filed July 12, 1915. Serial No. 39,474.

To all whom it may concern:

Be it known that I, ZALMON G. SHOLES, a citizen of the United States, residing at Wilmington, in the State of Delaware, have invented certain new and useful Improvements in Removable Mounting for Type-Writer Carriages; and I do hereby declare the following to be a full, clear, and exact description of the invention, such as will 10 enable others skilled in the art to which it appertains to make and use the same.

The present invention relates to an improvement in the supporting framework and type bar connections of a typewriter, and 15 the principal object of the invention is the provision of a construction whereby the assembling and taking apart of the machine are facilitated, more particularly with respect to removal of the carriage and the 20 parts borne by it.

The invention is illustrated in a preferred form in the accompanying drawings, wherein—

Figure 1 is a plan view of the frame as 25 assembled, certain attached parts being shown in section. Fig. 2 is a sectional view on the line 2—2 of Fig. 1, the carriage being partly shown in elevation, Fig. 3 is a detail plan view of the connections for operating 30 the tabulating or stop bar, and Fig. 4 is a partial elevation of the connection between the carriage and the spring feeding drum.

The top of the frame is made in the usual manner having the two flat sides 10 and 11, 35 the front crossing portion 12 and the rear flat portion 13, having a suitable opening 14 to permit passage of the elements which control the carriage.

The platen 15 is carried as usual by a carriage 16, preferably supported on ball bearings 17 and an upright framework 18 which is attached, as by screws 19, to a removable plate 20.

The front edge of the plate 20 is provided 45 with projections 21 which fit into corresponding cavities in the main frame, as clearly shown in Fig. 2. When the machine is assembled, the rear edge of the removable plate 20 is suitably secured to the main frame, and I have shown the two studs or 50 catches 22 and 23 for this purpose. These studs are revolvably mounted in the top of the main frame. The upper stud 22 is shown in Fig. 1 as occupying the position

given it when the parts are assembled for 55 use, while the stud 23 is turned so as to free the removable plate.

Beneath the carriage is the usual hook 24 which passes through an opening in the usual plate 25 on the end of the flexible connection 26, leading to the usual spring drum 27.

To control the tabulating or stop bar I employ upright rods 28, connected with tilting levers 29 and operated in a well known 65 manner. The upright rods 28 have inclined portions coöperating with the rod 30 fixed to the framework 18 for a well known purpose not concerned with this invention. In order easily to connect and disconnect the 70 bars 28 to and from the levers 29 I prefer to employ the means clearly shown in Fig. 3.

Each lever 29 is forked to receive the upper end of the bar 28, and a pin 31 passes through registering openings in the fork and 75 bar, being held in place by a spring 32. The pin 31 also passes through a bracket 33 on the lever 29, and has an enlarged head 34, by means of which the pin can be temporarily withdrawn by the fingers, when it is 80 desired to disconnect the lever and bar.

When the carriage is to be removed for any reason, the levers 28 are disconnected as just described, the plate 25 is removed from the hook 24, and the catches are turned 85 into the position shown at 23 in Fig. 1. The rear edge of the removable plate 20 is then lifted, and the projections 21 are withdrawn from their sockets. This frees the carriage and its supports, permitting their 90 complete removal from the machine.

The form and arrangement of the various parts can be modified in various ways without departing from my invention, and I do not limit myself to the details herein shown 95 and described.

What I claim is—

1. In a typewriting machine, a main frame having a fixed top plate formed with a depressed portion on its top surface and 100 having an opening in said portion, a removable plate fitting said depressed portion, a carriage support fixed to said removable plate, a carriage adapted to move along said support over said removable plate, means 105 for controlling said carriage extending upward through said opening, and means for securing said removable plate in place on

said fixed plate, and within said depressed portion thereof, substantially as described.

2. In a typewriting machine, a main frame having a fixed top plate formed with a depressed portion on its top surface, a removable plate fitting said depressed portion and having an inclined pin near one edge fitting a corresponding socket in said fixed plate, a carriage support fixed upon said removable plate, a movable carriage adapted to bear on said removable plate and guided by said support, and a clamping means for said removable plate adapted to engage the

edge opposite said pin, substantially as described. 15

3. In a typewriting machine, a main frame having a depressed portion in the back part of its top, a removable plate fitting said depression, a carriage support carried by said plate, a carriage on said support and means for temporarily fixing said plate on said main frame, substantially as described. 20

In testimony whereof I affix my signature.

ZALMON G. SHOLES.
